UNITED STATES PATENT OFFICE.

JOHN ROBERT GILL, OF LONDON, ENGLAND.

MEANS FOR TESTING FABRIC.

1,015,730.

Specification of Letters Patent.

Patented Jan. 23, 1912.

Application filed December 1, 1910. Serial No. 595,113.

To all whom it may concern:

Be it known that I, JOHN ROBERT GILL, a subject of the King of England, residing at London, England, have invented certain new and useful Improvements in Means for Testing Fabric, of which the following is a specification.

This invention relates to improvements in apparatus adapted for testing fabrics and comprising as its principal feature a magnifying device characterized by a microscope or magnifier and a screened source of illumination both integral parts of the construction and so combined as to constitute a portable self-contained unit.

Preferably the combination includes means arranged to illuminate the upper and under surfaces of the material, and a plate or slide containing a plurality of different openings, each of which openings is adapted to isolate the predetermined area of material below it so that the number of fibers in unit area can be conveniently counted.

A holding-down member for material beneath the magnifier can be used. A convenient construction of such holding-down member according to the present invention is one which is pivotally or otherwise so mounted on its support as to permit of the easy positioning below it of the margin of the sheet of material tested. Further, the holding-down member may be double-hinged so that it not only permits of the easy positioning below it of the margin of a sheet of material tested, but can be kept parallel with its support at different distances therefrom to suit the insertion below it of materials of differing thicknesses.

A convenient construction according to the present invention is illustrated in the accompanying drawings wherein—

Figure 1 is a vertical central section, and Fig. 2 is a plan.

Like letters indicate like parts throughout the drawings.

In the illustrated construction a case A to contain electric dry cells has the magnifying device B mounted on a lid A'. On the lid is an adjustable electric projector C supplied with current from dry cells contained in the lower portion of the case and serving to illuminate through an opening B' of the magnifier B the upper surface of the margin of a sheet of textile material T placed below the holding-down frame or member B² of the magnifier. Below the

holding-down member B² aforesaid, which has a window or opening B³ in it, is an opening A² in the lid, and within the casing, below the opening A² is a second projector 60 C² which projects light upward through the window in the casing so as to illuminate the under surface of that portion of the material which is below the holding-down member B². There is a lens B⁴ in the upper portion of the device B through which the material illuminated from above and below by the projectors C and C² can be conveniently viewed. The holding-down member B² is hinged to the casing by hinge-links 65 D and can therefore turn about the parallel axes at d¹ d² of the double-hinge thus constituted.

In the holding-down member is a slide E containing a plurality of differing openings 75 E¹ E² E³ each adapted to isolate a predetermined area of material below it.

The lamp of the upper projector C is hinged to its support, which is the pillar A⁴, so that it can be adjusted in the plane 80 containing that pillar, and the pillar is itself fitted to turn about its own axis thus enabling the lamp to be adjusted in a second plane perpendicular to the plane first mentioned. Suitable switches S are provided 85 for the lamps of the two projectors.

Instead of providing an electric generator within the casing A, the latter may be adapted to receive a plug connection of the usual or any other convenient type coupled 90 to, say, a wall-plug by a length of flexible conductor.

The source of illumination is so far screened from the eye of the user of the apparatus as not to send rays direct to the 95 eye. The projector C is hooded for this purpose, and for a like purpose the second projector C² is placed below the lid A¹. The second projector may be dispensed with.

What I claim as my invention and desire 100 to secure by Letters Patent is:—

1. In a magnifying device the combination of, a support for the material to be examined, a magnifier carried by such support, a source of light also carried by such support, a movable plate containing a plurality of different openings each adapted to isolate a predetermined area of the material under it, the whole apparatus being connected to the one support to constitute a 110 portable self-contained unit, substantially as set forth.

2. In a magnifying device the combination of, a support for the material to be examined having an orifice therein over which the material is placed, a magnifier carried by such support, a source of light carried on the same side of the support to illuminate one side of the material, a source of light on the other side of the support to illuminate the opposite side of the material 5 through the orifice in the support, means for bringing into operation either of these sources of light, and a movable plate containing a plurality of different openings each adapted to isolate a predetermined area 10 of material under it, the whole apparatus being connected to the one support to constitute a portable self-contained unit, substantially as set forth. 75
3. In a magnifying device the combination of, a support for the material to be examined, a magnifier carried by such support, a source of light also carried by such support to illuminate the material to be examined, and a hold-down pivotally connected to the support for holding the material to be examined, the whole apparatus being connected to the one support to constitute a portable self-contained unit, substantially as set forth. 80
4. In a magnifying device the combination of, a support for the material to be examined, a magnifier carried by such support, a source of light also carried by such support to illuminate the material to be examined, a hold-down for the material to be examined, and a plate movably mounted on the hold-down and containing a plurality of different openings each adapted to isolate a predetermined area of the material 35 under it, the whole apparatus being connected to the one support to constitute a portable self-contained unit, substantially as set forth. 85
5. In a magnifying device the combination of, a support for the material to be examined having in it an orifice over which the material is placed during examination, a magnifier carried by such support, a source of light carried on the same side of the support to illuminate one side of the material, a second source of light situated on the opposite side of the support to illuminate the material through the orifice in the support, means for bringing into action either source of light, a hold-down for the material to be examined, and a plate movably mounted on the hold-down and containing a plurality of different openings each adapted to isolate a predetermined area 50 of material under it, the whole apparatus being connected to the one support to constitute a portable self-contained unit, substantially as set forth. 90
6. In a magnifying device the combination of, a support for the material to be examined, a magnifier carried by such support, a source of light carried on the same side of the support to illuminate one side of the material to be examined, a second source of light situated on the opposite side of the support to illuminate the material through the orifice in the support, a hold-down pivotally connected to the support and carrying the magnifier, the whole apparatus being connected to the one support to constitute a portable self-contained unit, substantially as set forth. 95
7. In a magnifying device the combination of, a support for the material to be examined having in it an orifice over which the material is placed during examination, a magnifier carried by such support, a source of light carried on the same side of the support to illuminate one side of the material, a second source of light situated on the opposite side of the support to illuminate the material through the orifice in the support, means for bringing into action either source of light, and a hold-down for the material to be examined connected to the support by a double hinge permitting it to lie flat on the material on the support, the whole apparatus being connected to the one support to constitute a portable self-contained unit, substantially as set forth. 100
8. In a magnifying device the combination of, a support for the material to be examined, a magnifier, a source of light carried by such support to illuminate the material to be examined, and a hold-down hinged to the support and carrying the magnifier, the whole apparatus being connected to the one support to constitute a portable self-contained unit, substantially as set forth. 105
9. In a magnifying device the combination of, a support for the material to be examined having in it an orifice over which the material is placed during examination, a magnifier, a source of light carried on the same side of the support to illuminate one side of the material to be examined, a second source of light situated on the opposite side of the support to illuminate the material through the orifice in the support, means for bringing into action either source of light, and a hold-down hinged to the support and carrying the magnifier, the whole apparatus being connected to the one support to constitute a portable self-contained unit, substantially as set forth. 110
10. In a magnifying device the combination of, a support for the material to be examined having in it an orifice over which the material is placed during examination, a magnifier carried by such support, an adjustable source of light carried on the same side of the support to illuminate one side of the material to be examined, a hood movable with said source of light for preventing direct rays therefrom reaching the eye of the observer and reflecting same onto the material, a hold-down pivotally and hingedly connected to the support and carrying the magnifier, the whole apparatus being connected to the one support to constitute a portable self-contained unit, substantially as set forth. 115
11. In a magnifying device the combination of, a support for the material to be examined having in it an orifice over which the material is placed during examination, a magnifier carried by such support, a source of light carried on the same side of the support to illuminate one side of the material to be examined, a hood movable with said source of light for preventing direct rays therefrom reaching the eye of the observer and reflecting same onto the material, a hold-down pivotally connected to the support and carrying the magnifier, the whole apparatus being connected to the one support to constitute a portable self-contained unit, substantially as set forth. 120
12. In a magnifying device the combination of, a support for the material to be examined having in it an orifice over which the material is placed during examination, a magnifier carried by such support, a source of light carried on the same side of the support to illuminate one side of the material to be examined, a hood movable with said source of light for preventing direct rays therefrom reaching the eye of the observer and reflecting same onto the material, a hold-down pivotally connected to the support and carrying the magnifier, the whole apparatus being connected to the one support to constitute a portable self-contained unit, substantially as set forth. 125
13. In a magnifying device the combination of, a support for the material to be examined having in it an orifice over which the material is placed during examination, a magnifier carried by such support, a source of light carried on the same side of the support to illuminate one side of the material to be examined, a hood movable with said source of light for preventing direct rays therefrom reaching the eye of the observer and reflecting same onto the material, a hold-down pivotally connected to the support and carrying the magnifier, the whole apparatus being connected to the one support to constitute a portable self-contained unit, substantially as set forth. 130

connected to the support for holding the material over the orifice, a slide in the hold-down provided with a plurality of different openings for exposing a certain area of the material over said orifice, a second source of light situated on the opposite side of the support to illuminate the material through the orifice in the support, means for bringing into action either source of light, and an electric-battery for supplying current to the sources of light mounted in a compartment

formed in the support, the whole apparatus being connected to the one support to constitute a portable self-contained unit, substantially as set forth.

In testimony whereof I have signed my name to this specification in the presence of two subscribing witnesses.

JOHN ROBERT GILL.
